US00D747047S

(12) **United States Design Patent**
Cornwell et al.

(10) **Patent No.:** US D747,047 S
(45) **Date of Patent:** ** Jan. 5, 2016

(54) **AUTOMATIC PET FEEDING SYSTEM**

(71) Applicant: **Radio Systems Corporation**, Knoxville, TN (US)

(72) Inventors: **Jonathan L. Cornwell**, Powell, TN (US); **Melissa Poisson**, Knoxville, TN (US); **K. Michael Sayers**, Kodak, TN (US); "Boey" Song JiangHong, Shenzhen (CN)

(73) Assignee: **Radio Systems Corporation**, Knoxville, TN (US)

(**) Term: **15 Years**

(21) Appl. No.: **29/529,420**

(22) Filed: **Jun. 6, 2015**

Related U.S. Application Data

(60) Division of application No. 29/518,688, filed on Feb. 26, 2015, now Pat. No. Des. 736,481, which is a continuation-in-part of application No. 14/308,191, filed on Jun. 18, 2014.
